Primary Examiner — Lauren D McVey(74) *Attorney, Agent, or Firm* — Oblon, McClelland, Maier & Neustadt, L.L.P.(57) **CLAIM**

The ornamental design for a toner cartridge, as shown and described.

DESCRIPTION

FIG. 1 is a front and right side perspective view of a toner cartridge;

FIG. 2 is a partial enlarged front and right side perspective view of the section defined by lines 2-2 and 2'-2' in FIG. 1;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, bottom, and right side enlarged partial perspective view.

The evenly spaced broken lines in the figures illustrate portions of the toner cartridge that form no part of the claimed design. The dot-dash broken lines in the drawings form a boundary between claimed and unclaimed subject matter.
